Primary Examiner — Susan Bennett Hattan*Assistant Examiner* — Brett Miller(57) **CLAIM**

The ornamental design for a satellite, as shown and described.

DESCRIPTION

FIG. 1 is a front elevational view of a satellite showing my new invention;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of a satellite;

FIG. 8 is a right view thereof, showing the plane upon which a cross-sectional view is taken and shown in FIG. 9 and FIG. 10;

FIG. 9 is a perspective sectional view taken from section line A-A in FIG. 8 thereof; revealing the internal conveyor and support beam assembly; and,

FIG. 10 is a rear sectional view taken from section line A-A in FIG. 8 thereof.

The even length broken lines depict environment and form no part of the claim.

The dot-dot-dash broken lines depict section lines and form no part of the claim.

1 Claim, 10 Drawing Sheets(56)
